LOG- AND CARRIAGE-LOCKING SWINGING-
SAW SAWMILL

Edmond Lambert, Danielson, Conn.

Application April 17, 1944, Serial No. 531,463

6 Claims. (Cl. 143—46)

1

This invention relates to a saw mill especially adapted for cutting logs of tree length into desired or predetermined lengths, and has for the primary object the provision of a device of this character on which logs may be conveniently placed and secured against movement and a power driven saw easily movable relative to the logs and secured in any one of its several positions for cutting the log into determined lengths.

With these and other objects in view as will become more apparent, the invention consists in certain novel features of construction, combination and arrangement of parts as will be herein-after more fully described and claimed.

For a complete understanding of my invention, reference is to be had to the following description and accompanying drawings, in which

Figure 1 is a side elevation illustrating a saw mill constructed in accordance with my invention.

Figure 2 is an end elevation illustrating the device.

Figure 3 is a top plan view illustrating the log bed.

Figure 4 is a fragmentary vertical sectional view illustrating a clutch employed between the prime mover and the drive wheels of the device.

Figure 5 is a fragmentary sectional view, illustrating one of the wheels and its mounting on the device.

Figure 6 is an end elevation illustrating my modified form of the invention.

Figure 7 is a fragmentary side elevational view, illustrating the means of releasably securing the saw carriage to the log bed.

Figure 8 is a fragmentary top plan view showing the log bed equipped with keepers to operate in conjunction with my modified form of the invention.

Figure 9 is an end elevation illustrating several logs positioned on the bed and secured in place for sawing.

Figure 10 is a fragmentary end elevation illustrating several logs arranged on the bed and secured for sawing with the flexible element arranged between some of said legs.

Referring in detail to the drawings, the numeral 5 indicates a log bed, preferably of a size to accommodate thereon a log or logs of approximately tree length and includes relatively spaced transverse members 6 and longitudinally extending members 7. The members 6 and 7 are suitably secured together and arranged in superposed relation and paralleling the longitudinally extending members are rails 8 forming a track over

2

which a saw carriage 9 may move, either manually or by motive power. The rails 8 rest on the transverse members 6 and are suitably secured thereto. Also secured to the transverse members are log blocks 10 having concave faces 11 to accommodate one or more logs.

Rollers 12 are journaled on the transverse members to facilitate sliding of a log endwise of the bed to properly position the log on the bed for cutting into determined lengths. The rollers are preferably removably mounted on the bed. After the log has been positioned for cutting into determined lengths it is moved from the rollers transversely of the bed into the seats 11 of the blocks. It is preferable that the rollers 12 be located adjacent the blocks so that the distance in which the log must be moved from the rollers to the seats of the blocks will be very short.

The saw carriage 9 includes a frame 13 equipped with flanged type wheels 14 engaging the rails 8 of the track and guided thereby during the movement of the carriage endwise of the bed in either direction.

A platform 14' is carried by the frame 13 and has mounted thereon an internal combustion engine or some other type of prime mover, indicated generally by the character 15. The engine is belted to a power shaft 16 journaled on the frame and which extends longitudinally thereof.

30 A saw carrying lever 17 is journaled on the power shaft and extends transversely of the carriage to be manually manipulated in an upward and downward direction and has journaled thereon a circular type saw 18 belted to the power shaft.

35 As the saw 18 may be raised and lowered manually and is driven by the prime mover, it provides a convenient way in which the log on the blocks may be severed, the saw cutting the log in a downward direction. The operator having hold 40 of the lever can govern the cutting action of the saw on the log.

A manually actuated lever 19 is pivotally mounted on the frame 13 and includes a log securing fork 21 provided with tines 22 for biting 45 into the log when the fork is brought into straddling relation with the log, as shown in Figure 2. An upward movement of the lever 19 will free the fork 21 from the log and a downward movement of the lever will bring the tines 22 of the fork into biting relation with the log and also bring the ends of the fork into keepers 24. The keepers 24 are arranged in pairs and are mounted on the transverse members 6 of the bed, so that the saw carriage can be secured against accidental movement in several selected positions to

permit cutting of the log into determined lengths by the saw. This is accomplished by bringing the fork 21 into a pair of the keepers 24. The fork also being in engagement with the keepers and biting into the log prevents accidental movement of the log in the seats of the blocks while being acted on by the saw.

It will be noted that as the log is sawed in two, one adjacent end portion of the severed section is supported on one of the transverse members 6 of the bed 5 so that the opposite and unsupported opposite end portion of the sawed length may gravitate downwardly during the cutting operation and thus tend to move the end face of the section being severed away from the opposed face of the saw and thus prevent the saw from binding in the log, this being accomplished by the saw cutting the log always adjacent one of the transverse members 6 of the bed 5. In this connection, it is also noted that the remainder or unsawed portion of the log is supported and held tightly and immovably on the bed seat portions 10 by the fork 21. Then, too, if the sawed length of the log is long enough to extend across two or more of the bed seats 10 it is substantially supported and thus there is no dipping or sagging tendency thereof to cause binding on the saw blade.

As shown in Figure 10, the fork 21 may be provided with an additional number of tines to that shown in Figure 2, and also, as shown in Figures 9 and 10, a plurality of logs may be arranged on the blocks at one time for sawing into determined lengths and be secured thereon by the fork. It is preferable that two logs be arranged lowermost and a third log disposed thereabove and said third log may be separated from the lowermost logs by transverse flexible elements 25 arranged therebetween, as shown in Figure 10. The flexible elements may be in the form of pieces of rope which will assist in preventing the logs from binding the saw as it cuts through the logs. The fork may form an integral part of the lever or it may be separate and secured thereto in any well-known manner.

A power shaft 26 (see Figure 4) is journaled on the frame 43 and is connected to a pair of the wheels 44 by endless sprocket chains 27 and sprocket gears 28. The lower sprocket gears 28 are secured fixedly on axle extensions 30 of at least a pair of the track wheels 44 (see Figure 2). A conventional type of clutch 29 is connected to the engine 45 and the shaft 26. This construction permits moving of the carriage over the bed by the engine at the will of the operator to bring the saw into the different selected cutting positions. If desired, the clutch may have in combination therewith a reversing gear mechanism of a conventional construction so that the carriage may be made to travel in either direction by the engine over the log bed.

Referring to my modified form of invention shown in Figures 6 and 7, the carriage 9 is equipped with a reciprocating saw 33 to act on the log supported by the blocks of the bed. The saw 33 is of the buck type, consisting of a frame 34 and a saw blade 34' carried thereby. The frame 34 is slidably mounted on vertically arranged guide rods 35. The guide rods 35 are slidably mounted on a horizontally arranged rod 36 carried by the carriage. A pitman block 37 is slidably mounted on guides 38 carried by the carriage and is connected to the frame 34 of the saw by a pitman 43. Another pitman 39 is eccentrically pivoted at one end on a drive disc 41 secured to a power shaft 42 journaled on the carriage and

belted to the prime mover 15, as shown at 40. The opposite end of the pitman 39 is pivotally attached to the pitman block 37. The prime mover is supported on the platform of the carriage. This arrangement will bring about reciprocation of the saw 33 by the prime mover and the saw as it cuts through the log may move downwardly due to the frame 34 being slidably mounted on the vertically arranged rods 35. This saw may be provided with suitable raising and lowering means (not shown) which may be similar to the raising and lowering means for the aforesaid circular saw.

To secure the carriage in any one of its several selectable cutting positions in this form of my invention, a latch rod 45 is slidably mounted on the carriage and may enter keepers 46 on the bed and may be engaged and disengaged with and from said keepers through the pivotal movement of a hand lever 47 pivoted to said latch rod and on the carriage.

From the foregoing description taken in connection with the accompanying drawings, it will be seen that a saw mill has been provided which can be conveniently set up for use and is capable of accommodating logs of considerable lengths such as the substantially full length of a tree trunk and that the device is capable of cutting such logs into desired or predetermined lengths through a minimum effort on the part of the operators. The saw being power driven as well as the carriage being movable relative to the logs by power, reduces to a minimum the amount of manual effort necessary in the operation of this device.

While I have shown and described the preferred embodiment of my invention, it will be understood that minor changes in construction, combination and arrangement of parts may be made without departing from the spirit and scope of the invention as claimed.

Having thus described my invention, what I claim is:

1. In a saw mill, a selectively positionable saw carriage, a power driven saw mounted on said carriage for cutting action in a downward direction, an elongated log bed having the carriage mounted to slide longitudinally thereon and including a longitudinal series of spaced seats for supporting a log at intervals throughout the length of a log placed longitudinally thereon so that each log section as cut by the saw is supported so as to prevent binding of the saw, keepers on said bed, and a locking device mounted movably on the carriage to engage any one of the keepers with relation to which the carriage is selectively positioned for securing the carriage in saw cutting position, said locking device including means to engage the log to secure the latter against lateral, rotary and longitudinal movements on the seats when said locking device is in engagement with a keeper.

2. In a saw mill, an elongated bed, a longitudinal track on said bed, means for supporting logs longitudinally on the bed, a carriage including wheels to engage the track for the support of the carriage and its movement longitudinally of the track, a prime mover carried by the carriage, means for driving at least one of the said wheels by the prime mover whereby to move the carriage, means for locking the carriage in selected positions on the bed whereby to position the carriage selectively for the cross cutting of the supported log on the bed into sections of determined lengths, said means also fastening

the positioned log on its supporting means on the bed, a saw element mounted movably on the carriage in working relation to the positioned log on the bed and having an operative connection with said prime mover for its cutting action under the power of said prime mover, and means for moving said saw element into and out of cutting relation to the positioned log.

3. In a saw mill, an elongated bed, a longitudinal track on said bed, means for supporting logs longitudinally on the bed, a carriage including wheels to engage the track for the support of the carriage and its movement longitudinally of the track, a prime mover carried by the carriage, means for driving at least one of said wheels by the prime mover whereby to move the carriage, means for locking the carriage in selected positions on the bed whereby to position the carriage selectively for the cross cutting of the supported log on the bed into sections of determined lengths, said means also fastening the positioned log on its supporting means on the bed, vertically arranged guides mounted on the carriage, a saw frame slidably mounted vertically on said guides, means supporting said guides on the carriage for movement of the guides transversely of the carriage, a saw connected to the saw frame and movable therewith, and a drive means between the prime mover and the saw frame.

4. In a saw mill of the character described and including an elongated bed, said bed having a longitudinal series of transverse supporting blocks thereon and formed with concaved upper seating portions, a saw carrying carriage movable longitudinally of said bed and trackways provided therefor on the bed, and locking means carried by said carriage and cooperable with said block elements of the bed whereby to hold the carriage in selected positions on the bed for the cross cutting of logs supported longitudinally of the bed on said blocks, the concaved portions of said blocks being arranged and adapted for the reception of a plurality of logs placed longitudinally therein and in parallel relation to each other, and said locking means carried by said carriage having an arched portion positionable over the supported logs on said blocks of the bed in the engaging relation of said locking device with one of said blocks and said arched portion of the locking device having internal means for gripping and holding the logs on the blocks.

5. In a saw mill, a selectively positionable saw carriage, a power driven saw mounted on said carriage for cutting action in a downward direction, an elongated log bed having the carriage mounted to slide longitudinally thereon and including a longitudinal series of spaced seats for supporting a log at intervals throughout the length of a log placed longitudinally thereon so

that each log section as cut by the saw is supported so as to prevent binding of the saw, keepers on said seats, and a locking device mounted movably on the carriage to engage any one of the keepers with relation to which the carriage is selectively positioned for securing the carriage in saw cutting position.

6. In a saw mill, an elongated bed, a longitudinal track on said bed, means for supporting logs longitudinally on the bed, a carriage including wheels to engage the track for the support of the carriage and its movement longitudinally of the track, a prime mover carried by the carriage, means for driving at least one of the said wheels by the prime mover whereby to move the carriage, means for locking the carriage in selected positions on the bed whereby to position the carriage selectively for the cross cutting of the supported log on the bed into sections of determined lengths, said means also fastening the positioned log on its supporting means on the bed, a saw element mounted movably on the carriage in working relation to the positioned log on the bed and having an operative connection with said prime mover for its cutting action under the power of said prime mover, and means for moving said saw element into and out of cutting relation to the positioned log and operable from the same side of the carriage as the means for locking the carriage in a selected position.
